UNITED STATES PATENT OFFICE

JOSEPH R. RICHER, OF OAK PARK, ILLINOIS

ROTARY PUMP OR BLOWER

Application filed June 29, 1927. Serial No. 202,261.

My invention aims to provide a simple and cheaply constructed, noiseless and gearless pump or blower which will have a high capacity in proportion to its size and speed of 5 rotation, and which will produce relatively little friction even when moving viscous liquids.

More particularly, my invention provides a pump or blower in which a vane continuously forms a partition between three walls on a rotor, in which the vane is rotated by engagement with these walls without requiring interposed gears or other driving connections, and in which the vane continuously 15 contacts with all three of the said walls. Moreover, my invention provides a pump or blower of this type in which the shape of the vane and of the vane-engaging walls can easily be designed with a high degree of accuracy; and in which the vane may be flat-sided, while the said walls may be portions of cylinders, thereby facilitating their accurate manufacture.

Still further and also more detailed objects 25 will appear from the accompanying drawings and from the following specification, in which specification I am using the term pump in a generic sense in which it also includes blowers.

In the drawings,

Fig. 1 is an end elevation of a rotary pump embodying my invention, with the nearer end plate detached.

Fig. 2 is a central and vertical section 35 through the pump casing at right angles to the driving shaft.

Fig. 3 is a horizontal section taken along the axis of the driving shaft in Fig. 2 and looking upward.

Fig. 4 is a perspective view of the winged rotor.

Fig. 5 is a perspective view of the end plate of the casing, which has the stationary vane shaft attached to it.

Figs. 6 to 10 are diagrammatic views showing five consecutive positions of the winged rotor and of the pivoted vane with respect to the inlet and outlet chambers of the casing.

Fig. 11 is a diagram showing the method 50 of generating the curvature of the inner or

vane-engaging faces of the wings on the rotor.

Fig. 12 is a perspective view of a modified form of vane, namely one provided with end rollers.

In the illustrated embodiment, the casing 55 of my pump comprises a tubular portion 4 having two heads attached to it, including a head 1 carrying a journal 2 for the driving shaft 3. The tubular casing portion 4 has its major bore portion cylindrical but enlarged in diameter medially of the length of this casing portion to afford two diametrically opposite recesses 5 and 6 which respectively have an inlet pipe 7 and outlet pipe 8 connected to them, so that the said recesses 60 respectively form the inlet and the outlet chambers of the pump. Each of these recesses extends for somewhat less than 180 degrees around the bore of the tubular casing portions, thus leaving between them two bore 70 portions 9 and 10 of a common cylindrical curvature, which are diametrically opposite each other.

The driving shaft 3 which extends through the journal 2 is fast upon and may be integral 75 with a disk 11 which fits the cylindrical bore of the tubular casing portion, and this disk carries three segmental wings A, B and C, each of which has its outer face of a cylindrical curvature rotatably fitting the said bore 80 of the tubular casing portion. The three segmental wings are uniformly spaced circumferentially about the shaft 3 and present convexed faces toward each other and towards the said shaft, and the shaft does not project beyond the wing-carrying disk portion of the rotor which comprises the said shaft, disk and wings.

The companion head 12 which is fitted and fastened to the other end of the tubular casing carries a fixed shaft 13 which has its axis parallel to the axis of the driving shaft 3 but spaced from the latter along the medial axis 14 of the cylindrically curved bore parts 9 and 10 of the tubular casing member. Pivoted 85 at its own center on this stationary shaft 13 is a vane 15 which continuously has its periphery in engagement with all three of the inwardly directed faces of the wings on rotor, thereby continuously varying the relative 95

sizes of the three compartments (D, E and F) into which the partition-forming vane divides the substantially Y-sectioned interior of the rotor.

5 To secure this continuous contacting of the vane with the segmental wings, I form each end of the vane 15 as a hemisphere about an axis 16, as shown in Fig. 11, so that the circle 17 drawn about the pivot axis 18 of the vane through the axes 16 of the vane will form the pitch line of the vane in rolling on the segmental faces of wings of the rotor. Then I generate the curvature of the inner segment faces by rolling this pitch circle 17 on the 10 inside of the pitch circle of the tubular casting, which is a circle centered at the driving shaft axis 19 and of a radius equal to the distance between this axis 19 and the further vane-end axis 16 along a line also extending 15 through the vane shaft axis 18.

In practice, I preferably proportion the 20 parts so that the distance from 16 to 19 in Fig. 11 is just three times the distance between the driving shaft axis 19 and the vane 25 axis 18, and make the radius of each vane-end equal to the said distance between the axes 18 and 19. With these proportions, the generated curve (which is a hypocycloid) is a circle of a radius six times the distance between the 30 axes 18 and 19, so that each inner wing face can be turned on a lathe; and the main segment-engaging faces of the vane can be flat. By doing this I also cheapen the manufacture 35 of the vanes, as only their ends need to be milled and the needed cutter for the milling can easily be shaped with a high degree of accuracy.

Each of the opposed cylindrical bore portions 40 9 and 10 of the casing has a circumferential length somewhat greater than the width of the vane, and hence greater than the gap between the ends of any two adjacent segmental wings, so that either of these bore portions will effectively close any of these 45 gaps in certain positions of the rotor.

With the rotor rotating in a clock-wise direction, and the inlet at the right, the inlet space E beyond the end of the vane is quite small when that end first reaches the inlet 50 chamber of the pump, as shown in Fig. 6. This space gradually increases—as shown in Figs. 7 and 8—and reaches its maximum when the said main member and the vane are in the positions shown in Fig. 9, in which position the lower end of the space E is closed by the tubular bore portion 10, so that the space E holds its maximum capacity. As soon as this lower end of the space E passes beyond the left-hand end of the tubular portion 55 10 (of Fig. 3), this space opens into the outlet chamber 6. Then the continued movement of the vane gradually reduces this space until the parts reach the position of Fig. 10, in which position the vane has pushed almost all of the charge out of the space E.

The same action is repeated for each of the other spaces D and F, so that my simple pump has an intake and a discharge three times during every revolution. Moreover, the liquid storage space in the rotor is relatively large 70 in proportion to the diameter of this member, so that my pump has a large operating capacity in proportion to its size.

At the same time, the proportion of the pumped liquid which is adjacent to the periphery of the rotor is quite small, and the vane (which rotates three times for every two revolutions of the winged rotor) rolls to a large extent upon the segmental wings, so that the friction is quite small. Consequently, my pump is particularly advantageous for 80 use with liquids of high viscosity, thus making it suitable for pumping heavy lubricating oils. However, it can also be used for other liquids and even for gases, as for example for 85 furnace blowers.

During the operation of the pump, it will be seen from Figs. 6 to 10 that the vane slides its end K consecutively into and out of the consecutive arms of the substantially Y 90 shaped interior of the rotor, and the same holds true of the other end of the vane. Each vane-end draws liquid into one arm of this Y shaped interior and then forces liquid out of another arm, so that the vane acts effectively 95 both as a partition and as a plunger or piston.

In practice, and particularly for use with viscous liquids, I desirably provide some clearance between the extreme outward position of a vane end (as shown by the top of the vane in Fig. 1) and the bore portions 9 and 10 of the casing. This is easily done by making these casing portions of a radius somewhat larger than the distance from the 100 driving shaft axis 19 (in Fig. 11) to the top of the vane in that figure, and correspondingly increasing the diameter of the outer faces of the wings.

However, while I have illustrated and described my invention in an embodiment including a three-piece casing and a single-piece vane, I do not wish to be limited to the construction and arrangement thus disclosed, since many changes might obviously be made 115 without departing either from the spirit of my invention or from the appended claims. For example, I may provide the vane with revoluble-end portions as shown in Fig. 12, and the driving power might be applied to 120 the vane.

Since the winged rotor and the vane rotate conjointly, my pump may be driven from either of these two members, as the vane could obviously be fastened to a rotatably mounted shaft while leaving the rotor freely journaled. However, I preferably apply the driving power to the rotor which is much heavier than the vane. During the rotation, it will be noted from Figs. 6 to 10 inclusive that the 125 130

vane always has a considerable portion disposed in one of the arms of the Y-sectioned chamber in the rotor, so that the vane is moved by power applied at a considerable 5 distance from the pivot axis of the vane in directions substantially at right angles to the longitudinal medial plane of the vane taken through the semi-circles at its ends. Consequently, I transmit power to the vane 10 with very little friction and without any material thrust toward the pivot axis of the vane.

Moreover, it will be understood that the simultaneous contacting of the vane with all 15 three of the wings on the rotor, as shown in the drawings, is theoretical. In practice, I preferably provide a little clearance between these parts so as to allow a film of the oil or other pumped liquid to be disposed between 20 them. I may also vary the shape of the ends of the inner wing faces, as the shape of these is relatively immaterial, as long as the intervening main portions of these inner wing faces are hypocycloidal.

25 I claim as my invention:

1. In a rotary pump, a rotor and a vane pivoted at its center on a stationary axis parallel to but spaced from the axis of the rotor, the said rotor including three equally spaced 30 segmental wings having inwardly directed convex faces continuously engaging the vane, the vane having two flat and parallel edges constituting the major portion of its periphery and adapted to roll on the said convex 35 faces, each such wing face being a portion of a cylindrical surface whose radius is six times the spacing between the axis of the rotor and the pivot axis of the vane.

2. In a rotary pump, a rotor, and a vane 40 pivoted at its own center on a stationary axis parallel to but spaced from the axis of the rotor, the rotor including three wings having inwardly directed convex faces of arcuate circular section, and the vane being continuously in engagement with all three of the said 45 wing faces, the cross-sectional shape of the vane transverse of its pivot axis comprising two semi-circles concaved toward each other and connected by parallel lines.

50 3. In a rotary pump, a rotor, and a vane pivoted at its own center on a stationary axis parallel to but spaced from the axis of the rotor, the rotor including three wings having inwardly directed convex faces of hypocycloidal section, and the vane being continuously in engagement with all three of the said 55 wing faces, the cross-sectional shape of the vane transverse of its pivot axis comprising two semi-circles concaved toward each other and connected by parallel lines, the centers of 60 the semi-circles being twice as far from the pivot axis of the vane as the latter axis is from the axis of the rotor.

65 4. A rotary pump comprising a rotor having three spaced peripheral wings, and a vane

pivoted at its own center on an axis parallel to but spaced from the axis of the rotor, the vane being disposed between the said wings, each wing having its inner and outer faces portions of cylindrical surfaces; in combination with a casing having opposed bore portions fitting the said cylindrical surfaces and having inlet and outlet connections between its said opposed bore portions, the radius of the outer face portion of each wing being two-thirds that of the inner face of the wing. 70 75

5. A pump as per claim 1, in which the radius of the outer cylindrical surface portion of each wing is two-thirds that of the inner cylindrical surface portion of the wing. 80

6. A rotary pump, comprising a casing having opposed bore portions of a common cylindrical curvature, and having inlet and outlet connections between the said bore portions; a rotor coaxial with the said bore portions and having three equally spaced segmental wings; and a bar-like vane journaled between the said wings on an axis parallel to but spaced from the axis of the rotor; the vane having flat sides connecting two semi-cylindrical ends, the radius of each vane end being equal to the spacing between the said axes, and the distance between the axes of the semi-cylindrical end curvatures being four times the said spacing; each wing having as 90 its inner face a portion of a cylindrical surface whose radius is six times the said spacing. 95

7. A rotary pump comprising a stationary casing, a rotor mounted in the casing, the rotor having three symmetrically disposed and 100 counterpart segmental wings, and a vane pivoted upon the casing on a pivot axis parallel to but spaced from the axis of the rotor; the segmental wings all having their outer faces in a common cylindrical surface coaxial with 105 the rotor and of a radius four times the spacing between the said rotor and pivot axes; each segmental wing having its inner face in a cylindrical surface of a radius six times the distance between the rotor axis and the pivot 110 axis of the vane; the vane having opposed flat and parallel edges spaced by twice the distance between the said axes, and having semi-cylindrical end edges connecting the said parallel edges, the axis of each semi-cylindrical 115 end edge being spaced from the pivot axis of the vane by twice the distance between the said pivot axis and the rotor axis.

8. In a rotary pump, a rotor having adjacent to its periphery three counterpart and 120 symmetrically disposed wings freely spaced from each other by openings and presenting inwardly bowed inner faces, and a vane pivoted on a stationary pivot axis parallel to the axis of the rotor; each of the said inner wing faces being a portion of a cylindrical surface of a radius six times that of the spacing between the rotor axis and the pivot axis of the vane, and each such inner wing face approaching the axis of the rotor to a minimum 125 130

distance twice the said spacing; the vane being shaped for continuously engaging all three segmental walls and so that a medial edge portion of the vane will move along one of the said walls with a combined rolling and sliding movement while one end of the vane moves away from one of the openings and the other vane end moves into the next opening.

9. A rotary pump comprising a rotor having three symmetrically disposed and counterpart segmental walls freely spaced from one another at their ends by openings each of a given circumferential length, the transverse section of each such wall in a plane at right angles to the axis of the rotor being a portion of a cylindrical surface whose radius is three times the said circumferential length; and a vane pivoted on a stationary axis spaced from the rotor axis by one-half the said length, the vane having two opposed parallel edges spaced by the said length and adjoined by semi-cylindrical end edges, the total length of the vane being three times the said circumferential length.
